ROLL PAPER DISPENSER

William J. Shalhoub, North Bergen, N. J.

Application December 20, 1944, Serial No. 568,982

4 Claims. (Cl. 242—55.5)

This invention relates to paper dispensers, more particularly to roll paper dispensers, and aims to provide certain new and useful improvements therein whereby the housing of the dispenser may be attached to a wall or other support and the paper issuing from the roll through an opening in the housing may be readily torn off at the desired length in a simple and efficient manner.

Although the device has been designed primarily for a roll of wax paper such as is found in every home kitchen, it may of course be used for other kinds of paper and for other purposes. In addition to other desirable features, the device possesses the advantage of simple removal of the used up roll and insertion of a fresh roll of paper.

The above and other objects will become apparent in the following description, wherein characters of reference refer to like-numbered parts in the accompanying drawings. It is to be noted that the drawings are intended for the purpose of illustration only, and that it is neither desired nor intended to limit the invention in any manner to the particular details of construction shown excepting insofar as they may be deemed essential to the invention.

Referring briefly to the drawings, Fig. 1 is a perspective view of the dispenser ready for use in the kitchen.

Fig. 2 is a cross-sectional view taken on the line 2—2 of Fig. 1, showing the hinged front or cover in partly lowered condition.

Fig. 3 is a longitudinal sectional view taken on the line 3—3 of Fig. 1, with the roll of paper removed.

Fig. 4 is a partial reproduction of Fig. 3, with the roll of paper mounted in the device.

Fig. 5 is a cross-sectional view taken on the line 5—5 of Fig. 4.

Fig. 6 is a longitudinal sectional view also taken on the line 3—3 of Fig. 1, the front or cover being omitted and the roll of paper being indicated in position in broken lines, with the roll supports or hubs mounted in position.

Fig. 7 is a perspective view, enlarged, of one of the two end support members for the roll hubs.

Fig. 8 is a central vertical sectional view of the support shown in Fig. 7.

Fig. 9 is a perspective view of the other of the said two end support members, showing the axial hub locking member in extracted position.

Fig. 10 is a side elevational view of one of the two substantially identical roll supporting hubs.

Referring in detail to the drawings, the numeral 10 indicates the rear section and 11 the front section of a box-like housing, the latter being hinged to the former at 12, that is, along the bottom edges of both sections. The rear section 10 is provided with spaced holes 13 so that it may be secured against a wall, not shown, whence the front section 11 may be swung down therefrom on the hinges 12, as shown in Fig. 2.

10 As shown, the front section 11 is deeper than the rear section 10, and comprises the end walls 14, the front wall 15, and the bottom wall 16. At the junction of the front wall 15 with the bottom wall 16, a wide longitudinal slot 17 is provided in the former, and an overhang or lip 18 is formed along the forward edge of the bottom wall 16. The conformation of the lip 18 in cross-section, as shown in Fig. 2, is such that a sufficiently sharp edge is provided along which the paper may be torn, but the edge nevertheless is smooth so that there will be no danger of cutting the fingers of the person using the device. Intermediate the length of the front wall 15, the slot 17 is enlarged at 19 to provide access to the roll of paper to feed it down toward the slot with the fingers in case the same should be required.

The housing 10—11 may of course be made of any desired or suitable material, but it is believed that the most desirable would be a suitable plastic material, of which a large assortment is now available on the market.

30 The rear section 10 of the box comprises the rear wall 20, the end walls 22, the top wall 21, and the bottom wall 23. Secured by rivets 24 or by any other suitable means, against the inner sides of the end walls 22, are a pair of parallel support plates 25 which extend forward beyond the confines of the walls of the rear section, substantially as shown. These supports are substantially rectangular in conformation excepting for their outer ends, which are rounded. A rectangular opening 26 is provided through the member 25 about the center of curvature of the rounded end 27. A resilient finger 28 has its base secured at 29 to the outer side of each support, and at its free end has a substantially rectangular boss 30, which is substantially wedge-shaped in end view and is urged by the spring 28 into and through the opening 26 into the position shown in Fig. 7. Its extremity 31, which extends beyond the boss, serves as a thumb flap to draw the boss out of the opening 26 against the force of the spring 28, as shown in Fig. 9.

35 The support plates 25 are shown in position within the housing in Figs. 2, 3, and 4, with the

bosses 30 in their normal positions, that is, protruding through the openings 26. For each support 25 there is provided a hub member 31, and the latter comprises a disc 32 having a hub of reduced diameter, 33, extending integrally from one side thereof. An axial rectangular opening 34, of substantially the same dimensions as the bosses 30 excepting that they are sufficiently larger to permit registering of the ends of the bosses therein, is provided through each disc 31 and its boss 33. A radial cut-out 35 is provided through a portion of each disc beyond the peripheral edge of its boss, as seen in Fig. 10, and the surface of the back of the boss between the base of said cut-out and the opening 34 is beveled as shown in Figs. 6 and 10, at 36, and of course the disc is cut away behind the said bevel. The discs 32 are placed on the ends of the roll or cylinder of cardboard 37 on which the waxed paper 38 is rolled, with the hubs 33 registering in the openings of the cylinder. The paper is then inserted into the dispenser by sliding the discs 31 into the positions shown in Fig. 6, and in sliding them home with the cut-outs 35 first passing over the bosses 30, the beveled surfaces 36 push back the bosses 30; and when the discs 31 reach home, the springs 28 will force the bosses 30 through the openings 34 in each disc and its hub. Thus, the roll of paper will be secured in rotating condition, that is, when the free end or edge of the paper is pulled the roll of paper can rotate on the hubs 33. To remove the cardboard cylinder when the paper has been used up, the extremities 31' of the springs 28 are forced back by the thumb to release the discs 31, whence they with their hubs are readily removed.

Any suitable means may be provided for releasably locking the front section 11 against the rear section 10 when the roll of paper is mounted ready for use. One such means is illustrated, and comprises a tongue or finger 39 secured at its base at 40 on the top wall 21 of the rear section. On its free end the tongue 39 is provided with a depending button 41. The top wall 42 of the front section is provided with a detent or opening therethrough, shown at 43, with a groove 44 provided with a floor sloping upward toward the opening 43 from the edge of the said top wall. It is apparent that when the front section is swung into closing position, the button 41 will ride in the groove 44 and then fall into the opening 43 to releasably lock the front section in closed position. The extremity 45 of the tongue 39 serves as a means to lift the button out of the opening 43 to permit swinging open of the front section 11.

In Fig. 1 the edge of the waxed paper 38 is shown in broken lines extending beyond the slot 17. In use, this is grasped and pulled out until the desired length is obtained, and the paper is

then torn off against the edge 18. When a piece of the paper is again desired, it is advanced a sufficient distance outward by inserting a finger through the enlargement 19 and the paper is fed forward until it can be grasped for tearing off after, of course, being unwound the desired distance.

The invention above described provides substantial convenience to the user, in that it is not necessary to fumble with a box in order to obtain the desired sheet of paper, as is customarily necessary with containers of rolls of waxed paper. The dispenser is readily refilled as set forth, and it remains always out of the way yet neat and attractive in appearance and ready for immediate use.

Obviously, modifications in form and structure may be made without departing from the spirit or scope of the invention.

20 I claim:

1. A roll paper dispenser comprising a base adapted to be secured against a wall or the like, plates secured at their bases to the ends of said base and extending forward therefrom parallel with each other, the outer ends of said plates being semi-circular in conformation and having substantially rectangular openings therethrough positioned at the center of curvature of said semi-circular ends, spring fingers secured at one end to the outer surfaces of said plates and having bosses on their free ends adapted to register in said openings, said springs normally urging said bosses through said openings, discs having hubs thereon being slidably mounted against the inner sides of said plates, said hubs being adapted to have the ends of a cylinder of a roll of paper rotatably mounted thereon, said discs and hubs having axial openings therethrough in alignment with said plate openings, said bosses projecting through said last-named openings.

2. The device set forth in claim 1, said bosses being substantially rectangular in cross-section, said last-named openings being substantially rectangular in cross-section.

45 3. The device set forth in claim 1, said discs having radial cut-outs provided with beveled floors.

4. The device set forth in claim 1, said base having walls surrounding the top, bottom, and sides thereof to form one section of a box or the like, a complementary box section hinged at the bottom to the bottom wall of said base, means for releasably locking said second section against said first section in box-forming position, one wall of said second section having a longitudinal slot therethrough adapted to have the paper of said roll pass therethrough, one edge of said slot providing a tearing edge.
